OF INDIANAPOLIS, INDIANA.

AIR-LIFT PUMP.

No. 923,169.

Specification of Letters Patent.

Patented June 1, 1909.

Application filed October 30, 1908. Serial No. 460,197.

To all whom it may concern:

Be it known that I, OTTO E. HARRIS, a citizen of the United States, residing at Indianapolis, in the county of Marion and 5 State of Indiana, have invented certain new and useful Improvements in Air-Lift Pumps, of which the following is a specification.

The object of my invention is to produce 10 an air-lift pump of such construction as to produce a maximum outflow with a minimum amount of air.

The accompanying drawings illustrate my invention.

15 Figure 1 is an axial section of an air-lift pump embodying my invention; Fig. 2 a section, on an enlarged scale, on line 2 2 of Fig. 1; Fig. 3 a perspective detail of the upper end of the cylinder nozzle; Fig. 4 a 20 similar view of a modified form.

In the drawings, 10 indicates the main body of the pump, said body preferably having a suitable strainer 11 at its lower end. Formed within body 10 is a main 25 water-chamber 12 and an air-passage 13, said air passage at its lower end being inwardly and upwardly turned, as at 14 to receive a primary nozzle 15 which is preferably contracted at an intermediate point in 30 its length as shown at 16. At the bottom of chamber 12 is a spider 17 having a central ring in which is threaded the lower end of a secondary nozzle 18 the lower end of said secondary nozzle surrounding nozzle 16 35 with its interior communicating freely at its lower end with the interior of strainer 11, the chamber 12 also communicating freely with the interior of said strainer through the spaces between the arms of the 40 spider 17. The secondary nozzle 18 is extended upwardly in the main chamber 12 for a considerable portion of the length of said chamber and at its upper end said secondary nozzle is rendered permeable by a 45 multiplicity of outlets which begin some distance below the top of the secondary nozzle. In Figs. 1, 2 and 3 said outlets are shown as substantially axial slits 21, and in Fig. 4 they are shown as drilled openings 50 22. Threaded into the upper end of body 10, in line with chamber 12 thereof, is a coupling 23 into which is threaded, at 24, the upper end of a tubular gathering bell 25 the flared lower end 26 of which extends 55 downward over and embraces the per-

meable upper end of the secondary nozzle, the annular space 27 forming a communication between the lower end of the gathering bell and chamber 12.

Secured to the upper end of coupling 23 60 is a discharge pipe 28 which is led upward to the top of the well. Secured to body 10, in alignment with the air passage 13, is an air supply tube 29.

In operation, the structure shown in Fig. 65 1, is immersed to a sufficient depth in the water and air under pressure is forced through passages 29 and 13 and the primary nozzle 15 thus causing the water and air to flow upward through the secondary nozzle 70 18. As it reaches the upper permeable end of the secondary nozzle the stream of combined air and water issues not only in a direct line from the upper end of the secondary nozzle but also spreads laterally so as to 75 fill, and tend to seal, the lower end of the gathering bell 25, the stream continuing however to move upward and therefore draw upward, into the gathering bell; the body of water in the lower end of chamber 12. I 80 have found by experiment that, by making the upper end of the secondary nozzle permeable for an appreciable distance, the efficiency of the device is materially increased.

I claim as my invention:— 85

1. An air lift pump comprising an upwardly directed air nozzle, a tube of greater diameter than the air nozzle arranged with its lower end open to a water supply and embracing the upwardly directed portion of 90 the air nozzle, and having its upper end permeable for a distance below its upper extremity, and a second pipe of larger diameter than the first pipe with its lower end embracing the permeable upper end of the 95 first pipe at a distance therefrom and open to the water supply.

2. An air lift pump comprising an upwardly directed air nozzle, a tube of greater diameter than the air nozzle arranged with 100 its lower end open to a water supply and embracing the upwardly directed portion of the air nozzle, and having its upper end permeable for a distance below its upper extremity, and a second pipe of larger diameter 105 than the first pipe with its lower end embracing the permeable upper end of the first pipe at a distance therefrom and open to the water supply below the permeable upper end of the first pipe. 110

3. An air-lift pump comprising a main tubular body, an air nozzle arranged therein and discharging upwardly, a secondary nozzle of greater diameter than the primary nozzle and having its lower end embracing said primary nozzle and communicating with the fluid supply, said secondary nozzle having a permeable upper end, and a gathering bell embracing the permeable upper end of the 10 secondary nozzle and communicating with the fluid supply surrounding the secondary nozzle.

In witness whereof, I have hereunto set my hand and seal at Indianapolis, Indiana, this twenty-third day of September, A. D. 1915
one thousand nine hundred and eight.

OTTO E. HARRIS. [L. S.]
